UNITED STATES PATENT OFFICE.

ETHAN I. DODDS, OF AVALON, PENNSYLVANIA, ASSIGNOR TO PRESSED STEEL CAR COMPANY, OF PITTSBURG, PENNSYLVANIA, A CORPORATION OF NEW JERSEY.

CAR PART.

SPECIFICATION forming part of Letters Patent No. 780,269, dated January 17, 1905.

Application filed February 26, 1904. Serial No. 195,343.

To all whom it may concern:

Be it known that I, ETHAN I. DODDS, of Avalon, Allegheny county, Pennsylvania, have invented a new and useful Car Part, of which the following is a full, clear, and exact description, reference being had to the accompanying drawings, forming part of this specification, in which—

Figure 1 shows in plan view a flanged blank from which my improved car part is made. This blank may be a section of an I-beam, as shown in Fig. 2, a channel-beam, as in Fig. 3, or a Z-bar, as in Fig. 4, these figures being end views of the blank. Fig. 5 is a side view of a car-stake made in accordance with my invention. Fig. 6 is an elevation of the stake. Figs. 7, 8, and 9 are end views of the stake when made, respectively, from an I-beam, a channel-beam, and a Z-bar. Fig. 10 is an end view of the car-stake shown in Fig. 7 when braced by the application of an angle-bar. Fig. 11 is an end elevation of a modified construction of stake braced marginally with angle-bars.

In making car-stakes in accordance with my present invention I take a blank, such as shown in Figs. 1, 2, 3, and 4, which is a flanged beam, either an I-beam or channel-beam or a Z-bar, and divide it longitudinally through the web with a bias cut *b b* and also with transverse angular cuts *c c*, thus cutting out pieces of metal *d*, which may be discarded as scrap. These cuts produce two pieces of metal 2 2, each of which has along one edge the original marginal flange 3 of the beam from which it is made, while its other edge is cut. This piece is of suitable form to constitute a car-

stake, and to better adapt it for this purpose I place it in a suitable die or other apparatus, by which its cut edge is flanged, as shown at 4 in Figs. 5, 7, 8, and 9. I prefer to reinforce and strengthen the car-stake further by riveting to it a reinforcing-angle 5 opposite to the flange 4, as shown in Fig. 10.

In Fig. 11 I show a modification in which the car-stake 2 has no integral flange 4; but instead thereof reinforcing-flanges 5' 5" are riveted along the cut margin of the stake on both sides.

Within the scope of the invention as defined in the claims the skilled mechanic will be able to modify the construction in various ways, since

What I claim is—

1. A car part consisting of a single rolled beam having along one edge an integral rolled flange and having the other edge an angled cut edge reinforced by a marginal flange; substantially as described.

2. A car part having along one edge an integral rolled flange and having the other edge an angled cut edge reinforced by an integral marginal flange; substantially as described.

3. A car part having along one edge an integral rolled flange and having the other edge an angled cut edge reinforced by an integral marginal flange and with an attached angle piece; substantially as described.

In testimony whereof I have hereunto set my hand February 25, 1904.

ETHAN I. DODDS.
